UNITED STATES PATENT OFFICE.

FREDERICK DOEBELI, OF NEW YORK, N. Y., ASSIGNOR TO A. SIEGRIST CO., OF NEW YORK, N. Y., A COPARTNERSHIP.

DESIGN FOR BRAID.

No. 39,944.

Specification for Design.

Patented April 27, 1909.

Application filed February 5, 1909. Serial No. 476,332. Term of patent 7 years.

To all whom it may concern:

Be it known that I, FREDERICK DOEBELI, a citizen of the United States, and a resident of the borough of Brooklyn, county of Kings, city and State of New York, have invented a new, original, and ornamental Design for Braid, of which the following is a specification, reference being had to the accompanying drawing, forming a part thereof.

The figure is a front or face view of the braid.

I claim:

The ornamental design for braid, as shown.

FREDERICK DOEBELI.
